UNITED STATES PATENT OFFICE.

HARRY W. BURGNER, OF SINKING SPRING, PENNSYLVANIA.

LIQUID-SOAP HOLDER.

No. 922,453.

Specification of Letters Patent.

Patented May 25, 1909.

Application filed June 30, 1908. Serial No. 441,162.

To all whom it may concern:

Be it known that I, HARRY W. BURGNER, citizen of the United States, residing at Sinking Spring, in the county of Berks and State of Pennsylvania, have invented certain new and useful Improvements in Liquid-Soap Holders, of which the following is a specification:

This invention relates to improvements in liquid soap holders and the object is to provide a device for holding the soap in such a manner that it may be easily tapped and one in which the container may be easily and conveniently removed and replaced.

The device is intended to serve as an economizer as well as to supply a sanitary means of dispensing soap and it is intended more particularly for public wash stands.

The invention is more fully described in the following specification and clearly illustrated in the accompanying drawing, in which:

Figure 1 is an elevation of my device in position. Fig. 2 is a longitudinal sectional view of the tap.

The numeral 1 designates the supports, of which there are three, and they are held together by means of a disk 2 formed with wings 3 adapted to be bolted, one to each member 1. The disk has a central perforation 4. If desired the support may be secured to the wall as shown in Fig. 1, by means of a suitable bracket 5.

The numeral 6 designates the liquid soap container. This is preferably in the form of a bottle, in inverted position, and held between the supports 1.

The numeral 7 designates the tap. This comprises a right-angled tube, the vertical end 8 of which is inserted in the bottle neck and it is formed with an annular collar 9

against which the mouth of the bottle rests. This collar in turn rests on the upper surface of the disk 2 around the opening 4. In this vertical portion of the tap I secure a vent tube 10 adapted to extend into the bottle and above the surface of the liquid; the lower end passes through the bottom of the tap thus providing air to the bottle to prevent a vacuum.

The horizontal portion of the tap is formed with a valve seat 11 near its end and the extremity of this portion of the tap is screw threaded internally and in this end I place a valve screw 12, the extremity of which is tapered, as shown at 13, to form a valve adapted to seat against and close the opening in the seat 11. In the lower side of the tap, just outside of the valve seat, I form an outlet in the form of a depending tube 14.

It is evident that a slight turn of the valve screw will open or close the valve opening, and allow the liquid to flow from the outlet.

Having thus described my invention, what I claim is:

In a device of the class described a support comprising three members joined together by a disk, a removable liquid soap container adapted to be held in said support, a right angled tap secured to said container, a valve seat in said tap, a screw valve adapted to seat against said valve seat, a vent tube passing through said tap and communicating with the outside atmosphere and the upper portion of said container, and a bracket for holding said support in position.

In testimony whereof I affix my signature, in presence of two witnesses.

HARRY W. BURGNER.
